HONING MACHINE

William D. Schmidt, Worcester, Mass., assignor
to The Heald Machine Company, Worcester,
Mass., a corporation of Massachusetts

Application November 5, 1936, Serial No. 109,270
Renewed May 4, 1938

22 Claims. (Cl. 51—165)

The present invention relates to a honing machine, and especially to a machine in which the honing operation is under the control of a size determining mechanism.

5 In the accurate honing of workpieces to a predetermined finished dimension, it is frequently desirable to provide for measuring the size of the workpiece in order to terminate the honing operation when the predetermined finished size 10 is reached. A honing machine adapted for use with a plug gage is described and claimed in a co-pending application of Harold L. Blood, Serial No. 102,147, filed September 23, 1936, in which, however, the supporting structure for the honing stones must be shifted axially toward one end of 15 the workpiece to allow entry of the plug gage at the opposite end. This arrangement is entirely satisfactory in operation, but, where the workpiece is relatively short, the hones cannot be reciprocated sufficiently relative to the workpiece to 20 remain in contact with the workpiece and, at the same time, allow the plug gage to test the workpiece diameter. One of the principal objects of the present invention is to avoid the above noted 25 objection by a gage which is in a radial plane which passes through the honing members.

The amount of material removed in the usual honing operation is relatively small, and in many cases is no more than one or two ten-thousandths 30 of an inch. A further object of the present invention is the provision of an extremely sensitive gage, which will measure small variations in workpiece diameter, of the order above noted, to provide for controlling the finished diameters of 35 successive workpieces within extremely small limits.

Where a honing machine is arranged for the simultaneous honing of a plurality of workpieces, with one hone operating on each workpiece, it is 40 frequently desirable where accurate sizing is essential, to provide for terminating the honing action of each hone independently, so that the finished size of each workpiece may be individually controlled. A further object of the invention 45 is to provide a size control associated with each honing head in a multiple-head honing machine, with a provision for rendering each hone inoperative when the workpiece operated upon by the hone reaches a predetermined size, 50 independently of the action of the other hones on the machine.

Other and further objects and advantages of the invention will more fully appear from the following detailed description, taken in connection with the accompanying drawings, in which—

Fig. 1 is a sectional view through a honing device embodying the invention, the end carrying the hone being shown.

Fig. 2 is an end elevation of the hone of Fig. 1, with parts broken away.

Fig. 3 is a sectional view through the hone of Figs. 1 and 2, substantially along the line 3—3 of Fig. 2.

Fig. 4 is a sectional view through the end of the honing device opposite to the end shown in Fig. 1.

Fig. 5 is a view of the end of the honing device shown in Fig. 4, with parts broken away along the line 5—5.

Fig. 6 is a diagrammatic view of a machine on which the honing device of Figs. 1—5 may be mounted.

Fig. 7 is a wiring diagram.

Like reference characters refer to like parts in the different figures.

The honing device disclosed in the drawings may be applied to any suitable type of honing machine which may be, for example, the honing machine described in the co-pending application of Harold L. Blood, Serial No. 100,911, filed September 15, 1936, which discloses a multiple-head honing machine. It is sufficient to note, for the purposes of the present invention, that one form of machine suitable for use with the honing head to be described, embodies a reciprocating table 1, Fig. 6, mounted on a base 2 and adapted to carry either a work-support or the honing device. In the construction shown, the work-support 3, in the form of a bracket, is secured to the table, and the honing device 4, embodying the invention, is mounted on a bridge 5, which extends over the table at one end of the base. The table is reciprocated for moving the workpiece or workpieces carried by the work-support axially into and out of operative engagement with the hone, and to provide for a short relative reciprocation between the workpiece and the honing device in operative position. This reciprocation may be provided by the cylinder 6 and piston 7, the latter being connected by a piston rod 8 to a lug 9 on the table. The control of the reciprocating table by a fluid pressure-actuated mechanism of this character, is so well known as to require no further description. It will be understood that the bridge may have a plurality of honing devices arranged in a row for engagement with a plurality of workpieces in the work-support, each workpiece being located in axial alignment with a corresponding honing device.

55

With reference now to Figs. 1 and 4, the honing device embodying the invention comprises a housing 10, see also Fig. 6, in which is journalled a rotary shaft 11, on one end of which a hone 12 is mounted. To the opposite end of the shaft 11 is secured a pulley 13, Fig. 4, by which a rotation of the shaft is obtained. Suitable belts provide a connection between the pulley 13 and a driving pulley, not shown, the belts being kept tight by an idler pulley 14 journalled on a stud 15 mounted on the bridge.

Referring again to Fig. 1, the hone 12, which corresponds, in general, to the hone described and claimed in the co-pending Blood application, Serial No. 100,580, filed September 14, 1936, comprises an arbor or head 16, having an axial bore 17, in which a spindle 18 is slidable, the latter being held against rotation in the arbor by a suitable key, not shown. The spindle 18 has an arcuate shoulder 19 positioned within the head, and the end of said spindle projects beyond the head and has a cap 20 secured thereto. A cylindrical hub 21 on the arbor provides for attachment thereof, with the honing members mounted thereon, to the end of the shaft 11, and the arbor is held against rotation on said shaft by a set screw 22, Fig. 3.

The arbor 16 has a plurality of radially extending slots 23, in each of which is positioned a bell crank lever 24. At the corner of each lever is an arcuate protuberance 25 engageable with the arcuate shoulder 19 on the hone spindle, thereby permitting oscillation of the lever about this point.

Surrounding the arbor adjacent the base of the slots 23 is a ring 26, secured to the head as by bolts 27, the ring having a small flange 28 engaging in an annular notch 29 in the arbor, to hold the ring in position. Between the ring and the arbor is clamped a resilient disk 30, in the form of an annular diaphragm having a plurality of resilient fingers 31, one of which extends inwardly into each of the notches 23. Each lever 24 has an arcuate lug 32 for engagement with the inner or left hand (Fig. 1) side of the corresponding finger 31.

The opposite end of each lever has an arcuate lug 33 which engages in an arcuate recess 34 in a hone carrier 35. On the outer side of each carrier is a plate 36 to which is secured, as by a suitable adhesive, a honing member preferably in the form of a stone 37, of abrasive material. The honing stones are additionally held on the carrier plates by flanges 38 extending outwardly from the plates.

The plates 36 are releasably held on the carriers by coil springs 39 and 40, each in the form of an annulus extending around the arbor. The spring 39 is positioned at the inner or left hand end of the plates and engages with the left hand edge of the flanges 38 thereon. The other coil spring 40 is positioned in a recess 41 in the outer end of each of the plates 36, the inturned portion of the plate which forms the recess engaging in a correspondingly shaped recess 42 in the carrier. These coil springs hold the plates on the carriers and hold the carriers in engagement with the corresponding levers 24. The levers are held in predetermined relation to each other by a coil spring 43, also in the form of an annulus, positioned in a slot 44 provided in the arbor. The several springs 39, 40 and 43 tend to collapse the hone and thus hold it releasably in contracted position.

75 The hone is expanded for moving the stones

outwardly into engagement with the workpiece by mechanism shown in Figs. 1 and 4, which may correspond in general to that disclosed in the copending application of Blood and Schmidt, Serial No. 103,725, filed October 2, 1936. With reference to these figures, the shaft 11 has an axial bore 45 in which the end of the spindle 18 is received. A rod 46, also positioned in the bore, has a plunger 47 on the right hand end thereof for engagement with the end of the spindle 18, and a coil spring 48 surrounds the rod 46 and urges the plunger 47 to the right for expanding the hone, the spring being positioned between the plunger and a collar 49 within the spindle. The rod 46 is held against turning movement within the spindle by a key 50, Fig. 4, which allows for an axial movement of the rod 46 to the right. Movement of the rod 46 is limited by a nut 51 on the threaded left hand end of the rod, said nut having a projecting flange engageable with the end of the pulley 13. A second nut 52 on the rod is held against turning movement relative to the nut 51 by a pin 53 extending through both of the nuts and a coil spring 54 positioned between the nuts and engageable in recesses therein urges the nuts apart to place a frictional drag thereon.

A compensation for wear on the stones is provided and the mechanism for this purpose may also correspond, in general, to that disclosed in the above cited copending application of Blood and Schmidt. The compensatory movement of the stones is effected by turning of the nuts 51 and 52 on the rod 46 to allow a slightly greater movement of the rod to the right and thus a greater expansion of the hone. With reference to Fig. 4, the nut 51 has a collar 55 extending therearound and in a position for engagement with a radial flange 56 on the nut 52. The collar is mounted in an open slot 57 in an arm 58 and is carried on trunnions, not shown, extending inwardly from opposite sides of the slot for a turning movement of the collar therein. The arm 58 is journalled on a pin 59 in a bracket 60 secured to the housing 10. A projecting bar 61, forming part of the arm 58, has an adjustable stop 62 engageable with a part of the bracket 60 and an adjustable stop 63 in the bracket 60 is engageable with the bar 61. The cooperating stops 62 and 63 limit the rocking movement of the arm 58 in both directions.

The lower end of the arm 58 has a plunger 64 slidably mounted therein and normally urged into the position shown by a spring 65 surrounding the plunger, the movement of the plunger to the right being limited by adjusting nuts 66 on the left hand end of the plunger. The latter is in a position for engagement with the end of the table 1 as the latter reaches operative position and an oscillation of the arm 58 occurs during the reciprocatory movement of the table while in operative position. In the normal oscillatory movement of the arm 58, the collar 55 does not come in contact with the flange 56. As the stones become worn, however, so that a compensation for wear is necessary, the flange 56 engages with the collar 55 as the hone is expanded and the nuts 51 and 52 are then held against turning movement until the rod 46 is turned slightly within the nuts to allow a greater expansion of the hone.

The above structure is all fully described and claimed in earlier patents and copending applications and does not of itself embody the present invention. The latter involves in connection with the above, or similar honing machine elements,

the attainment of the objects and novel features above set forth. In accordance with the present invention the honing operation is under the control of a gage or sizing device which will control the honing operation and procure desired changes in the honing operation when the workpiece reaches a predetermined size. The particular change described in the present embodiment of the invention is a termination of the honing operation when the workpiece reaches a predetermined finished dimension.

With reference again to Fig. 4, the nut 52 on the hone actuating rod 46 has, integral therewith, and extending to the left thereof, a flanged collar 67 to which a similar collar 68 is fastened, as by bolts 69. The collar 68 is secured by a key 70 to a piston rod 71 having at its opposite end a piston 72 which is slidable in a cylinder 73 in a housing 74 secured to the main housing 10. The cylinder 73 has a port 75 connected by a conduit 76 to a port 77 in a valve casing 78, Fig. 6, mounted on the base of the machine. The casing 78 has an inlet port 79 connected to a suitable source of fluid under pressure which may be a constant pressure pump.

An exhaust port 80 is also provided in the casing 78 and fluid connection between the port 77 and 80 is normally provided by a reduced portion 81 of a valve 82 slidable in the casing. At the end of the honing operation the valve 82 is shifted to the left by energization of a solenoid 83 which has its armature 84 connected to the valve stem. Movement of the valve to the left allows the admission of fluid under pressure to the right hand side of the piston 72 to collapse the hone, thereby withdrawing the stones from engagement with the workpiece. The solenoid 83 is energized when the workpiece reaches a predetermined dimension in response to the action of a gage, best shown in Figs. 2 and 3. With reference to these figures, the hone arbor 16 has diametrically opposed radial slots 85 and 86 in which are positioned the gage arms or feelers 87 and 88 respectively. The end of each arm has a hardened surface 89 for engagement with the workpiece and these surfaces, as shown in Fig. 3, are in a radial plane passing through the stones 37. That is to say, a plane at right angles to the axis of rotation of the hones which includes the hardened surfaces 89 will also pass through each of the honing stones 37; in this manner the gage arms engage with the workpiece surface during the honing operation and it is entirely unnecessary to withdraw the hone from the work in order to test the workpiece diameter.

The gage arms are carried by flat springs 90 and 91 connected to the ends of a bar 92 positioned in a slot 93 in the spindle 18 and pivoted on a pin 94, carried by the end of the spindle 11. Small slots 95 in the spindle 18 at right angles to the slot 93 allow the spindle 18 to move axially for expansion and contraction of the hone without affecting the position of the gage arms and supporting structure.

On the ends of the gage arms opposite to the work engaging surfaces are opposed coils 96 and 97, also positioned within the slot 93. The bar 92 has an integral finger 98 extending parallel to the arms, and with its free end located between the ends of the coils 96 and 97. Thus the gage and associated mechanism are "floated" on the pin 94 so that the gage is free to measure the workpiece diameter by the spacing of the hardened surfaces on the two gage arms, independently of the actual position of either arm relative to the hone.

The inner ends of the coils 96 and 97 are connected together by a lead 99, Fig. 3, which also extends centrally through the spindle 18 and actuating rod 46 to a ring 100, Fig. 4, of conducting material, extending around the collar 67 and 5 insulated therefrom by insulation 101. The outer ends of the coils 96 and 97 are connected by leads 102 and 103 respectively to rings 104 and 105, Fig. 3, of conducting material, extending around the periphery of an integral flange 106 on the 10 shaft 11, and insulated therefrom by suitable insulation 107, the leads 102 and 103 extending through small bores 108 and 109 in the shaft 11. The rings 104 and 105 are engaged by spring fingers 110 and 111 mounted on an insulating 15 block 112 secured to a cap 113 on the housing 10, and a similar spring finger 114, Fig. 4, engages the ring 100 and is mounted on an insulating block 115 on the cylinder housing 74. Suitable leads 116, 117 and 118 provide a connection from 20 these spring fingers to the remainder of the electrical system.

With reference now to the wiring diagram of Fig. 7, in which the rings 100, 104 and 105, and the spring fingers 110, 111 and 114 are omitted 25 for clarity, the coils 96 and 97 are shown to be connected by the leads 99 and 118 to one side of the secondary winding 119 of a transformer 120, whose primary winding 121 is connected to a source of power represented by the parallel leads 30 122. The outer end of the coil 96 is connected by the lead 116 to one terminal of one of a pair of primary windings 123 and 124, both wound in the same direction on a magnetic core 125. The outer end of the coil 97 is similarly connected by the lead 117 to the opposite winding 35 124. These windings 123 and 124 have their adjacent ends connected by a lead 126 to the secondary winding of the transformer 120.

A secondary winding 127 on the core 125 is connected by leads 128 and 129 to the opposite terminals of a suitable bridge rectifier 130 of familiar construction. The other terminals of this rectifier are connected by leads 131 and 132 to a coil 133 forming part of a micro-ammeter 134. 45 The indicating needle 135 of the micro-ammeter has its end in a position to engage with a conducting fluid 136 in a cup 137. The needle is connected by a lead 138 to one side of a suitable source of direct current represented by the parallel leads 138 and 139, and the cup 137 is connected by a lead 140 to one terminal of the solenoid 83. The opposite terminal of the solenoid is connected by a lead 141 to the lead 139.

As the workpiece is honed the gage arms move 55 apart, at the workpiece engaging ends, bringing the coils 96 and 97 closer and closer to the finger 98, thereby increasing the power in the windings 123 and 124 until the induced current in the secondary winding 127 reaches such a value as to 60 cause the needle of the micro-ammeter 134 to move into engagement with the conducting fluid. When this occurs the solenoid 83 is energized to 65 shift the valve 82, thereby directing fluid to the right hand side of the piston 72 for contracting 70 the hone. It will be apparent that the device can be accurately adjusted so that the solenoid 83 will be energized when the workpiece has been honed to a predetermined internal diameter, and that the device is sufficiently sensitive to permit 75 control of the workpiece diameter to within very close limits. A suitable adjustable resistance coil 142 by which to control the amount of current in the windings 123 and 124 may be provided for accurate adjustment.

In the operation of the machine the table 1 is caused to move to the left by any suitable control lever, which will cause the workpiece *a* to be brought into operative relation to the hone, or 5 in the case of a multi-head honing machine, to cause the several workpieces to be brought simultaneously into operative relation with the several aligned hones. When the workpiece or workpieces reach operative relation the gage fingers 10 are urged toward each other by engagement with the bore of the workpiece, thereby moving the coils 96 and 97 apart and reducing the amount of current through the micro-ammeter so that the needle is withdrawn from the conducting fluid to 15 break the circuit through the solenoid 83. The valve 82 is then shifted to the right by the spring 84' to allow fluid under pressure from the right hand side of the piston 72 to exhaust so that the honing stones may be moved outwardly by the 20 spring 48 into engagement with the workpiece bore.

The honing operation continues with the gage fingers gradually moving apart as material is removed from the workpiece bore until the workpiece reaches the desired finished size, at which 25 time the coils 96 and 97 are close enough together to induce sufficient current in the winding 127 to cause the needle of the micro-ammeter to complete the circuit through the solenoid 83. When 30 the solenoid is thus energized the valve 82 is shifted to the left to direct fluid under pressure to the cylinder 73 and withdraw the hone from engagement with the workpiece. Where the machine has several honing heads it will be apparent 35 that each individual hone is separately controlled by the gage fingers associated therewith, so that the finished size of each of the simultaneously honed workpieces may be individually controlled with the corresponding hone withdrawn 40 from operative relation to the workpiece as soon as each workpiece reaches the desired finished diameter.

From the foregoing it will be apparent that the present invention involves a size-control for a 45 honing machine which permits control of the honing operation. The size-control device has contact with the workpiece in a radial plane passing through the honing stones so that it is unnecessary to withdraw the hones far enough from 50 the workpiece to allow the entry of a gage of the plug type. Where the machine has a plurality of honing heads simultaneously operative upon a series of workpieces, it is possible, by the arrangement disclosed, to terminate each individual honing operation independently of the honing operations simultaneously performed by the other honing heads on the machine.

I claim:

1. In a honing machine, the combination with 60 a hone having a plurality of angularly spaced honing elements, of a size determining mechanism having a feeler engageable with the workpiece between adjacent honing elements.

2. In a honing machine, the combination with 65 a hone having a plurality of angularly spaced honing elements, of a size determining mechanism having a feeler engageable with the workpiece in a radial plane intersecting the honing elements.

3. In a honing machine, a hone having at least 70 one honing element, a size controlling mechanism having a feeler engageable with the surface of the workpiece in a radial plane intersecting 75 the honing element, and means under the control

of the sizing mechanism for withdrawing the honing element relative to the hone.

4. In a honing machine, the combination with 5 a hone having a plurality of angularly spaced honing elements, of a size controlling mechanism including at least one work engaging contact carried by the hone and engageable with the workpiece, said work engaging contact being positioned between adjacent honing elements.

5. In a honing machine, the combination with 10 a rotatable hone having a plurality of angularly spaced honing elements, of a size controlling mechanism having a feeler engageable with the workpiece and rotatable with the hone.

6. In a honing machine, a hone comprising an 15 arbor and a plurality of angularly spaced honing elements movable relative to the arbor, a size controlling mechanism carried by said arbor and including a feeler engageable with the workpiece and means actuated by said size controlling 20 mechanism for procuring a movement of said honing elements relative to said arbor in a direction to withdraw said elements from engagement with the workpiece.

7. In a honing machine, a hone comprising an 25 arbor and a plurality of angularly spaced honing elements movable relative to the arbor, a size controlling mechanism having at least one work engaging contact engageable with the workpiece in a radial plane intersecting the honing ele- 30 ments, and means under the control of said sizing mechanism for procuring a movement of the honing elements relative to the arbor for withdrawing the elements from operative position.

8. In a honing machine, the combination with 35 a hone having a plurality of honing elements, means for normally holding the elements in operative position, size determining mechanism having at least one work engaging contact engageable with the workpiece in a radial plane 40 intersecting the honing elements, and means actuated by said size determining mechanism for withdrawing the honing elements from operative position.

9. In a honing machine, the combination with 45 a hone having a plurality of honing elements, means for normally holding the elements in operative position, size determining mechanism having at least one work engaging contact engageable with the workpiece in a radial plane 50 intersecting the honing elements, fluid pressure actuated means for procuring movement of said honing elements relative to the hone out of operative relation, and means under the control of the sizing mechanism for rendering operative 55 said fluid pressure actuated means.

10. In a honing machine, the combination with a hone having a plurality of honing elements, means for normally holding the elements in operative position, size determining mechanism 60 having at least one work engaging contact engageable with the workpiece in a radial plane intersecting the honing elements, fluid pressure actuated means for procuring movement of said honing elements relative to the hone out of operative relation, and electrical means under the control of the sizing mechanism for rendering operative 65 said fluid pressure actuated means.

11. In a hone, an arbor, at least one honing element carried by said arbor and movable relative thereto into and out of operative position, and a gage member carried by said arbor and movable relative thereto said member having a feeler engageable with the workpiece.

12. In a hone, an arbor, a plurality of honing 75

elements carried by said arbor and movable relative thereto, and at least one gage member carried by said arbor and having a work engaging portion located between adjacent honing elements.

5 13. In a hone, an arbor having a plurality of radial slots therein, a lever positioned in each slot, a honing element carried by each lever, and a gage member carried by said arbor and having a work engaging portion located between adjacent honing elements.

10 14. In a hone, an arbor having a plurality of radial slots therein, a lever positioned in each slot, a honing element carried by each lever, and a gage member carried by said arbor and having a work engaging portion located between adjacent honing elements.

15 15. In a hone, an arbor having a plurality of angularly spaced honing elements carried by and movable relative to the arbor, at least one gage arm carried by said arbor and having a work engaging feeler positioned between adjacent honing elements, said gage arm being mounted for rocking movement relative to the arbor.

20 16. In a hone, an arbor having a plurality of angularly spaced honing elements carried by and movable relative to the arbor, and a pair of gage arms carried by the arbor and mounted for movement relative thereto, each arm having a feeler positioned between adjacent honing elements.

25 17. In a hone, an arbor having a plurality of angularly spaced honing elements carried by and movable relative to the arbor, a pair of gage arms carried by the arbor and mounted for movement relative thereto, each arm having a feeler positioned between adjacent honing elements, and means for normally urging said honing elements relative to the arbor into operative position.

30 18. In a hone, an arbor having a plurality of angularly spaced honing elements carried by and movable relative to the arbor, and an electrically actuated size controlling mechanism including at least one gage arm carried by the arbor and having a feeler position between adjacent honing elements for engagement with the workpiece, and electrically actuated means for procuring a

change in the honing operation in response to movement of the gage arm.

35 19. In a honing machine, a hone comprising an arbor, a plurality of angularly spaced honing elements movable relative to the arbor and a spring actuated plunger movable axially of the arbor for urging the honing elements into operative position, size controlling means including a gage arm carried by the arbor and having a work engaging contact positioned between adjacent honing elements, and means responsive to movement of the gage arm relative to the arbor for procuring a movement of the plunger for a contraction of the hone.

40 20. In a honing machine, the combination with a hone having a plurality of angularly spaced honing elements, of a size-determining mechanism having a feeler engageable with the workpiece between adjacent honing elements, and means under the control of said size-determining mechanism for withdrawing the hone from engagement with the workpiece.

45 21. In a honing machine, a hone comprising an arbor, a plurality of angularly spaced honing elements carried by and movable relative to the arbor, at least one gage arm carried by said gage arbor, and having a work-engaging feeler positioned between adjacent honing elements, said gage arm being mounted for rocking movement relative to the arbor, electrically actuated means for procuring a change in the honing operation, and means responsive to movement of the gage arm for rendering said electrically actuated means operative.

50 22. In a honing machine, a hone comprising an arbor, a plurality of angularly spaced honing elements carried by and movable relative to the arbor, at least one gage arm carried by said gage arbor, and having a work-engaging feeler positioned between adjacent honing elements, said gage arm being mounted for rocking movement relative to the arbor, electrically actuated means for procuring a change in the honing operation, an electrical circuit, and means responsive to movement of the gage arm for varying the power in the circuit, and means operative when the power in the circuit reaches a predetermined quantity for actuating said electrically actuated means.

55 WILLIAM D. SCHMIDT.
